WITNESS:

UNITED STATES PATENT OFFICE

HENRY ELMER BRIGGS, OF COLUMBIA FALLS, MONTANA, ASSIGNOR OF FOUR-TENTHS
TO NELS JOHN SMITH, OF COLUMBIA FALLS, MONTANA

CORK PULLER

Application filed June 28, 1929. Serial No. 374,570.

The object of this, my present invention, is the provision of an extremely simple, cheaply constructed but thoroughly efficient means for extricating corks from bottle necks without inflicting injury to the bottle or to the cork.

To the attainment of the foregoing the invention consists in the improvement herein-after described and definitely claimed.

10 In the drawings:

Figure 1 is a view illustrating the improvement in operative position, the bottle being in section.

Figure 2 is a perspective view of the improvement, on a somewhat enlarged scale.

Figure 3 is a sectional view approximately on the line 3—3 of Figure 2.

Fig. 4 is a view showing the elliptical portion and the tongue in section.

20 As disclosed by the drawings my improvement is preferably constructed from a single piece of resilient metal, and comprises a flat outer portion 1 that has its end rounded to form the same with a finger grip 2. The flat 25 portion has its sides gradually inclined inwardly and merges into a cross sectionally elliptical portion 3. The resilient or spring metal member from what I will term the inner face of the said elliptical portion is slotted both transversely and longitudinally to form the same with an outwardly directed curved spring finger 5, and from the finger the improvement is gracefully arched to the pointed end thereof, as indicated by the number 6.

By providing the improvement with the cross sectionally elliptical portion one face thereof will coincide with the curvatures in the neck of the bottle 7, and the opposite face 40 of the improvement will permit of the device being inserted between the neck and side of the cork 8 in the bottle without inflicting injury to the said cork, or in other words, by simply slightly depressing the cork. When 45 the device is moved to the position illustrated by Figure 1 of the drawings the spring finger 5 will be moved out of the depression that affords the pocket 9 therefor and will be brought against the inner face of the cork. A 50 pull upon the finger portion of the ring 2 will

cause the cork to be extricated in an easy and expeditious manner and without liability of injury to either the cork or to the bottle neck. The arched portion 6 when it rides against the inner wall of the neck will further force the 55 finger against the inner end of the cork as will, it is thought, be apparent.

My improvement comprises a small member which may be easily carried in the pocket of the user and the simplicity and advantages thereof will, it is thought, be apparent without further detailed description.

Having described the invention, I claim:

A cork extractor formed from a piece of resilient metal whose outer portion is flat 65 and which has its end rounded to afford a finger hold, the sides of the flat portion being gradually inclined inwardly and merging into a cross sectional elliptical portion whose end is arched and pointed, and said 70 elliptical portion being slotted transversely from one of its sides and further slotted longitudinally toward its arched and pointed end to provide a spring finger which is arched outwardly from the member but which when 75 depressed is fully received in the body of the said member.

In testimony whereof I affix my signature.

HENRY ELMER BRIGGS.
